US00D932552S

(12) **United States Design Patent** (10) **Patent No.:** **US D932,552 S**
Morisawa (45) **Date of Patent:** ** *Oct. 5, 2021

(54) **COVER FOR ELECTRONIC DEVICE**

(71) Applicant: **SONY INTERACTIVE ENTERTAINMENT INC.**, Tokyo (JP)

(72) Inventor: **Yujin Morisawa**, Tokyo (JP)

(73) Assignee: **SONY INTERACTIVE ENTERTAINMENT INC.**, Tokyo (JP)

(*) Notice: This patent is subject to a terminal disclaimer.

(**) Term: **15 Years**

(21) Appl. No.: **29/757,559**

(22) Filed: **Nov. 6, 2020**

(30) **Foreign Application Priority Data**

May 22, 2020 (JP) ..... 2020-010086 D

CLAIM

The ornamental design for a cover for electronic device, as shown and described.

DESCRIPTION

FIG. 1 is a perspective view of front, top and right side of a cover for electronic device showing my new design; FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the claimed design in a first environmental structure; and,

FIG. 10 is another perspective view showing the claimed design in a second environmental structure.

The broken lines in FIGS. 2 and 4-8 depict portions of the cover for electronic device that form no part of the claim. The broken lines in FIGS. 9 and 10 illustrate environmental structure and form no part of the claimed design.

1 Claim, 7 Drawing Sheets
